ELECTRICAL SIGNALING SYSTEM

Gerald Deakin, New York, N. Y., assignor to International Standard Electric Corporation, New York, N. Y., a corporation of Delaware

Application February 24, 1944, Serial No. 523,626

28 Claims. (Cl. 179—18)

1

This invention relates to new and useful improvements in electrical signaling and switching systems and more particularly to improved impulse sending and impulse receiving or registering arrangements for use in telecommunication switching systems such as automatic and semi-automatic telephone exchanges.

An object of the invention is to increase the speed and reliability with which control impulses may be transmitted from a first point to a second point, for example, from a sub-station or the like to a control exchange or other position where selecting equipment is located.

With this object in view, I provide an arrangement in which upon the extension of a line to a distant point at which a selective control is to be exercised, a source of alternating current is coupled to the line. A signaling device, such as a dial, is then actuated to periodically reverse the polarity of a uni-directional current conducting device, such as a dry contact rectifier, in the line circuit. At the distant point there is connected to the line circuit polarized relay means which responds to the reversals of polarity of the current flow and controls switching apparatus thereat.

The pulse cycle of the standard interrupter dial circuit at present used in automatic telephone exchange systems consists of a closure and an opening of a single stepping relay direct current circuit with a 60/40 ratio of opening to closure. One digit is recorded per cycle, and the opening of the circuit is the useful part of the cycle; the closure of the circuit represents time unavoidably wasted to prepare the circuit to receive the next pulse. In alternating current rectifier dialing circuits in accordance with my invention the complete pulse cycle consists of two pulses, a positive pulse and a negative pulse each one useful in recording a digit as well as in assisting the restoration of the relay which is operated by the preceding pulse of opposite polarity. For example, in a preferred arrangement in which two oppositely polarized relays are used for responding to the pulses, these two relays operate on a "push-up, push-back" principle and thus the complete cycle is used by both relays while rectification with polarization places the operation of the two relays 180° out of phase.

The positive and negative pulses consist in fact of trains of positive and negative pulses at the periodicity of the alternating current source, but for all practical purposes these integrated series of pulses act as though they were pulses of the direct current of the proper polarity. In the

2

alternating current impulsing circuits described hereinafter only the back contact of the pulsing relay is used and as it takes very little energy to break the back contact the combination of two oppositely polarized pulsing relays results in a very high speed dialling circuit.

The stepping relay as at present used in standard systems has to be adjusted (by the tensioning of a spring which is always difficult and somewhat unreliable) to work on both long and short lines. On short lines it becomes heavily magnetized while on long lines it is only partially magnetized. It must fall off quickly on short lines after being heavily magnetized and it must pull up quickly on long lines when weakly magnetized, and it must also fall back quickly on long lines in which appreciable energy may remain stored in the line due to its capacity which tends to retard the release of the stepping relay.

In the dialling system according to my invention, these disadvantages are overcome in a simple and efficient manner. When rectified alternating current is applied to the dialling circuit which is provided with a polarized relay, the relay is pulled up and forced back with equal energy and the effect of the residual energy stored in long lines is neutralized. When a back contact of the polarized relay is used for controlling the selective means only a small amount of energy is required to operate the circuit, all of which tends to make the circuit more sensitive and rapid in response.

These and other features and advantages of my invention will be more clearly understood from the following description of preferred embodiments thereof and the appended claims.

In the accompanying drawings:

Fig. 1 is a block schematic drawing showing sufficient of the layout of an exchange to give a clear understanding of the present invention;

Fig. 9 is an elevation partly in section taken on the line 9—9 of Fig. 8;

Fig. 10 is a section taken on the line 10—10 of Fig. 9;

Fig. 11 is a section taken on the line 11—11 of Fig. 9, and

Fig. 12 shows a detail of the spring nest in the rectifier dial.

Referring first to Fig. 2, the subscriber set circuit shown therein is apart from the rectifier dial of the usual type. The rectifier dial which will be described later in connection with Figs. 8 to 12 includes a rotating rectifier R and a home contact spring nest S. The operation of the rectifier dial from a circuit point of view is as follows: When the finger wheel is moved off normal a pin P3 allows spring B to break contact with spring C which removes a short circuit from the rectifier R, and to make contact with spring A which short circuits the induction coil and transmitter. Pin P1 causes spring F to break contact with spring G until shortly before the first finger hole reaches the finger stop; in other words, the line circuit is momentarily opened each time the finger wheel is turned to the finger stop. When the finger wheel is released the rectifier R makes one-half of a revolution for each finger hole passing the finger stop but before the last finger hole passes the finger stop P1 again opens contact between the springs F and G thereby momentarily opening the line circuit which causes the digit change-over in the register to take place. As will be clear from the subsequent description of the rectifier dial, the rectifier is always returned to its predetermined position of polarity. Thus, should an odd digit be dialed the rectifier is given a half revolution to restore it to its normal position while contact between springs F and G is open.

From what has been said above it will be seen that when the digit 1 is dialed the initial closure of the line through the rectifier R in its normal position sends the first pulse to record the digit 1 and that when the finger wheel is released the circuit is opened for the change-over before the rectifier reverses the current.

The sub-station set circuit shown in Fig. 2 is intended for use with a system incorporating registers of the kind shown in Fig. 4, in which a direct current loop is present over the subscriber's line until dialing actually commences. In an alternative method of operation alternating current is applied to the subscriber's line as soon as the register is connected up. In this case the subscriber's set circuit is as illustrated in Fig. 3. In this arrangement the contact springs F and G shown in Fig. 2, have been omitted as it is not necessary to open the line circuit when the rectifier dial is moved off normal.

The construction of a suitable rectifier dial is illustrated in Figs. 8 to 12 and will now be described. Referring first particularly to Figs. 9 and 10, the dial consists of two main parts, an upper part 1 housing the home contact nest HC and a lower part 2 housing the rotating rectifier S.

In the upper housing 1 is mounted a finger wheel 3 provided with the usual finger holes and attached to a shaft 4 which rotates in a sleeve

5 in the housing 1 when driven by a coiled spring 6, one end of which is attached to the finger wheel 3, while the other rests in a groove in the housing part 1. A segment 7 is attached to shaft 5 4 by nut 8. A pawl 9 is pivoted to the segment 7 and tends to engage the teeth of a ratchet wheel 10 under the tension of a spring 10a.

Ratchet wheel 10 and a gear wheel 11 are attached to each other and rotate freely on the lower extension of shaft 4. They are held in position by the flat head 11a of a bearing pin 12 when the lower part 2 housing the rectifier unit is mounted in position. Ratchet wheel 10 has a number of teeth corresponding to the number of positions of the finger wheel 3. Every other tooth is relatively long (in a radial sense). When the finger wheel 3 is in its normal position one edge of the segment 7 rests against a back stop 13 formed in the housing 1 and a raised surface 14 on the inner periphery of the housing 1 adjacent the stop 13 lifts the pawl 9 so that it engages only the deep teeth of a ratchet 10.

When the finger wheel 3 is rotated by the user, the segment 7 moves clockwise and when it has moved an angular distance equal to about one finger hole spacing the raised surface 14 no longer bears on the pawl 9 and the latter rotates slightly about its pivot so as to engage both the long and the short teeth of the ratchet wheel 10. Should the finger wheel be turned a distance equal to five finger holes, that is, should the digit 3 be dialed, since there is a space equal to two finger holes between the hole number 1 and the finger stop 19, the pawl 9 will engage a short tooth. When the finger wheel is released the spring 6 will rotate the ratchet wheel 10 counterclockwise. As the segment 7 approaches its home position, the pawl 9 engages the raised surface 14 and thus disengages the short tooth but reengages the next long tooth just before the segment 7 comes to rest against the back stop 13. The object of this arrangement is to insure that the rectifier S always returns to its predetermined position of polarity.

45 The home spring nest consists of five springs A, B, C, F and G, Fig. 10, mounted in a block of insulating material 39 fixed to the upper housing 1. Two pins P1 and P3 are mounted on the segment 7 in such position that when the finger wheel is moved off normal, pin P1 opens the contact between springs F and G, whilst pin P3 opens the contact between springs B and C and permits contact to be made between springs A and B. The segment 7 is of insulating material.

55 Assume now that the digit 1 is dialed. When the finger is placed in hole number 1, Fig. 8, and the finger wheel is moved off normal, pin P1 engages the tip 15 of the extension of spring F, Figs. 10 and 12, and breaks the normal contact between springs F and G. Spring F is cut away at its lower edge and provided with an inclined lip 16. When the hole number 1 has been moved an angular distance less than two finger hole spaces, pin P1 rides over the lip 16, Fig. 12, and disengages the spring F, so that when the finger reaches the finger stop 19 contact between springs F and G is again made. The three home contact springs, A, B and C are shown in their normal positions in Fig. 10. When segment 7 is moved off normal pin P3 disengages spring B thereby causing contact to be broken with spring C and made with spring A. The springs A, B and C remain in this position until the dial returns to 60 normal.

When the finger wheel 3 is released, after it has moved about three quarters of a finger hole space, pin P1 reengages the projecting lip 16 of spring F and again opens the contact between springs F and G. When segment 7 reaches its normal position against the back stop 13, contact between springs F and G is restored.

The lower part 2 houses the rectifier discs S Figs. 9 and 11. These are assembled on a bushing 21 of insulating material. Brush 20a is clamped against the rectifier disc on one side of the rectifier unit and brush 20b is clamped against the disc on the other side by means of nuts 22. A bearing pin 12 which passes through the bushing 21 has screwed to it a gear wheel 23 and rotates in bushings 24 attached to the upper and lower covers of the rectifier housing 2. The bearing pin 12 is grooved so that when it is slipped through the bore of the bushing 21 the rectifier assembly S and brushes 20a and 20b rotate with the bearing pin 12 and the gear wheel 23.

The upper and lower brushes 20a and 20b rub against collector rings 24a and 24b mounted on the inside wall of the housing 2 as shown in Fig. 11. The external connections are connected to the collector rings 24a and 24b. Gear wheels 11 and 23 are interconnected by pinions 25 which are attached to each other and held in position by a bearing pin 26 mounted in the lower end of the housing portion 2. The ratchet and gear wheels are assembled so that when the wheel 10 is in the position shown in Fig. 10 the rotating rectifier unit S is in the position shown in Fig. 11. The ratio of the various gears is such that the rectifier unit S makes one complete revolution when the finger wheel 3 moves an angular distance equal to two finger hole spaces.

The setting of brushes 20a and 20b, Fig. 11, is such that when they engage the insulating surfaces 27 between the collector rings 24a and 24b as position 2 of the ratchet wheel passes the normal position 1 on the return journey, the pin P1 engages lip 16 of the spring F and opens the contact between springs F and G. Thus the contact between these springs is opened before the brushes 20a and 20b make contact with the succeeding collector rings.

As speed control of a rectifier dial is not critical it is sufficient to weight the brushes 20a and 20b at their ends so that they act both as governor wings as well as collector brushes.

The method of operation of the improved dialing system as applied to an arrangement in which a direct current loop is present on the subscriber's line until dialing commences will now be described with reference to Figs. 1, 2 and 4.

Referring first to Fig. 1, when a calling subscriber removes his receiver a circuit is completed over the switch hook contacts for the line relay in the subscriber's line circuit, an R-link starter and chooser circuit selects an idle R-link, a register finder associated with which connects up an idle register and a B-link finder selects an idle B-link having associated therewith a first group selector and a second line finder. The calling line is picked up over the second line finder and an idle first line finder having access to the calling line. All these operations take place in the manner fully described in my co-pending application Serial No. 521,160, filed February 5, 1944, and form no part of the present invention.

The register shown in Fig. 4 is generally similar to the register described in my co-pending application referred to above and only that part of the circuit has been shown which relates to

rectifier dialing since it is believed that this will enable a clear understanding of the present invention without the introduction of unnecessary complication. When the calling line is picked up, relay RAR, RBR and RCR operate as described in the co-pending application referred to and relay HR is energized over a circuit from battery, the outer back contact of relay R1R, front contact of relay RBR, resistor R3 and the upper winding of relay HR to ground. Relay RBR locks up and deenergizes relay RAR as described in the co-pending application referred to. Relay HR locks up over both windings in series with the calling line and over its lowermost front contact completes a circuit for the slow release relay R1R. Relay R1R places battery on both windings of relay DR which are differentially disposed, thus relay DR will not operate as long as both of its windings are energized over back contacts of relays PR (+) and PR (-). Relay R1R removes battery from the resistor R3. Dialling tone is applied over transformer TT. The circuit remains in this condition until the subscriber commences to dial.

When the finger wheel of the rectifier dial is moved from its home position the pin P3 opens contacts B and C and removes a short circuit from the dial rectifier R and the line circuit is momentarily opened. Relay HR releases but not the slow release relay R1R. When the line circuit is closed again, this time through the rectifier R in the subscriber's set, current flows in such a direction as to energize polarized relay PR (+), Fig. 4. This current flows from the 400 cycle, 50 volt source over a guard lamp GL, back contacts of relay HR and RAR a wire, dial rectifier R at the sub-station, b wire and back contacts of relays RAR and HR. Relay PR (+) opens its back contact thus opening one winding of relay DR and causing it to operate. Relay DR energizes relay R3R, which closes a circuit for relay R4R. Relay DR completes a holding circuit for relay R1R over a back contact of relay HR. When relay HR closes its back contact, relay DTR operates, locks up and removes dialling tone from the subscriber's line.

The first pulse is always a positive pulse. The next pulse is a negative pulse which follows immediately after the first pulse and causes polarized relay PR (-) to open its back contact and relay PR (+) to close its back contact. This reversal takes place so rapidly that the differential relay DR which is very slightly slow releasing does not fall off. Relay DR thus remains in an unbalanced operated condition until pulsing is completed. The second or negative pulse operates polarized relay PR (-), which removes a short circuit from relay CR2 which locks up over its own front contact, resistor R4, and a front contact of relay R4R. The following or third and positive pulse energizes counting relay CR3 and so on.

When the series of pulses ceases, the line circuit is again momentarily opened by the pin P1 of the dial just before it comes to rest, as has already been explained in the preceding description of the construction of the dial. Relays PR (+) and PR (-) remain on their back contacts, thus the differential windings of relay DR are again closed in parallel and relay DR falls off and releases R3R. Relay R3R deenergizes relay R4R but before slow release relay R4R breaks its front contacts, a circuit is momentarily closed from battery, outer left back contacts of relay R3R, front contacts of relay R4R, resistor R3 and

the upper winding of relay HR to ground. Relay HR is again energized and locks up over the calling line, the circuit of which is now closed with the dial at rest.

Another circuit is also momentarily established from ground over the left hand back contacts of relay R3R and the front contacts of relay R4R to the counting relays CR. Assume, for example, that counting relays CR2 and CR3 have been energized. The aforementioned circuit is completed over the front contacts of relays CR2, CR3, back contacts of relay CR4, back contacts of relay TR1, resistor R5 and winding of relay XR3 to battery. When relay R4R breaks its front contact a short circuit is removed from relay TR1 which locks up in series with relay XR3 over a circuit extending from ground, front contacts of RCR, winding of relay TR1, front contacts of relay XR3 and winding of relay XR3 to battery.

It will be noted that depending upon which relays CR2 . . . CR10 are energized, the relays XR1 . . . XR4 are energized singly and in different combinations and over their contacts apply selective potentials PN1 . . . PN10 to the bank C of the out-control switch P0.

Relay XR3, for example, connects potential PN3 over its front contact and back contacts of relays XR1 and XR2 to terminal number 1 in the bank C of the out-control switch P0 which is the counterpart of the switch P0 in the register circuit fully described in my co-pending application previously referred to. Brush C is connected to the grid of tube V1 of the pair of testing tubes V1 and V2. The grid of tube V2 is connected to the b wire which extends over the register finder, the R-link, B-link finder and B-link to the first group selector (see Fig. 1). Relay TR1 grounds the a wire extending to the first group selector over brush B of switch P0 in its first position. When the a wire is grounded the first group selector hunts for a free trunk connected to potential PN3 and when such a trunk is found a gas valve (not shown) associated with the tubes V1 and V2 operates and causes the selector to be arrested, all substantially as described in my co-pending application already referred to.

Other XR relays or combinations of them are locked up when other digits are dialled and control the setting up of the connection. The four XR relays and the relay TR1, five in all, suffice to store one of ten digits. In a seven digit system there would be seven groups of these five relays. These groups of five relays have the same purpose as and replace the digit switches and the switch P1 of the register described in my co-pending application above referred to. They are not essential to the method of rectifier dialling disclosed herein but they are much quicker in operation than switches and for this reason have been employed in the register as described in this modification in the present application.

When relay R4R breaks its front contact the locked up counting relays CR2 . . . CR10 are released and the dialling circuit of the register is restored to normal and awaits the dialling of the next digit which when dialled causes the register to repeat the operations just described including, in this case, the locking up of the proper combination of the second group of XR relays.

It is not essential to use polarized pulsing relays in the register. As shown in Fig. 5 the polarized relays PR (+) and PR (-) may be replaced by ordinary relays R1 and R2, each connected in

series with oppositely polarized rectifiers S (-) and S (+), but with this arrangement dialling speed is reduced.

As already explained, in place of the method described with reference to Figs. 2 and 4 in which the subscriber's line is a direct current loop until dialling commences, an alternative method may be used in which alternating current is applied to the line as soon as the register is connected up. The subscriber's set circuit for this method of operation is shown in Fig. 3. In this case contact springs F and G are not required in the rectifier dial as it is not necessary to open the line circuit when the dial is moved off normal.

The register circuit for use with this method is shown in Fig. 6 and is similar to that of Fig. 4 but its operation differs in the following respect.

When, following the response of relays RBR and RCR, relay RAR makes its back contacts, alternating current is applied to the b wire of a calling line over the guard lamp GL, and as the rectifier R in the subscriber's set, Fig. 3, is short circuited alternating current returns over the a wire. Polarized relay PR (-) does not break its back contact because of the rapidly following positive and negative pulses. Relay PR (-), however, does break its back contact due to the presence of a rectifier S (-) which is in series with the polarized relay PR (-) in the pulsing circuit and which suppresses the positive pulse so far as relay PR (-) is concerned. Relay RBR which made its front contacts at the same time that relay RAR made its back contacts places battery on both windings of relay DR which are differentially disposed. When relay PR (-) breaks its back contact, differential relay DR is unbalanced and operates; relay DR energizes relay R3R which in turn energizes relay R4R. The circuit remains in this condition until dialling commences.

When the finger wheel of the dial is pulled off normal, the short circuit is merely removed from the rectifier R and current flows over the loop in a positive direction and energizes polarized relay PR (+). Relay PR (+) breaks its back contact but relay DR remains energized over the back contact of relay PR (-) which is forced back. Relay CR1 operates and locks up and in addition to connecting relay CR2 to the back contact of polarized relay PR (-) short circuits the rectifier S (-) so that pulsing may then take place without the handicap of any unnecessary impedance in the line circuit. The counting relays CR, the code relays XR and the TR relays operate as already described in connection with the register circuit shown in Fig. 4.

The digit change over takes place when the dial returns to its normal position and returns alternating current over the a wire due to the short circuiting of the rectifier in the dial. Since relay CR1 has short circuited the rectifier S (-), both the polarized relays PR (-) and PR (+) make their back contacts, thus the differential relay DR falls away and releases relay R3R which, as in the case of the register circuit shown in Fig. 4, first locks up the proper combination of XR relays in series with relay TR1 and then releases the counting relays CR ready for the dialling of the next digit. The relays XR apply a selective potential PN1 . . . PN10 to the bank C of the out-control switch P0 whereby the first group selector operates to select an idle outlet in a wanted group of lines.

Fig. 7 shows how a register circuit with digit and change-over switches of the kind fully dis-

closed in my co-pending application above referred to may be adapted for rectifier dialling using a subscriber's set circuit as shown in Fig. 2.

When the register has picked up the calling line relay RAR releases and relay RBR operates as described in the co-pending application referred to, after which the subscriber hears the dialling tone, the primary circuit of which is closed from a front contact of relay RBR, back contact of relay DTR, the primary winding of tone transformer TT and the dialling tone interrupter DTI to battery. Relay HR1 operates over a circuit extending from ground, back contact of relay R1R, front contact of RBR and one winding of relay HR1 to battery. Relay HR1 connects its second winding from ground to the *a* wire and connects relay HR2 from battery to the *b* wire. Relays HR1 and HR2 operate in series with the calling line and telephone circuit with the rectifier R, Fig. 2, short circuited. Relay HR1 operates slow release relay R1R which places battery on the two windings of a differential relay DR and ground on the armatures of the oppositely polarized relays PR (+) and PR (-). Relay DR does not operate at this time as its windings are differentially disposed. The magnet of the first digit switch D1 is energized over a circuit from ground, front contacts of relay R1R, back contacts of relay PR (+), brush A, terminal 1 of the in-control switch PI, terminal O, brush C of switch D1, winding of magnet D1 to battery. Magnet D1 attracts its armature but this switch is of the well known type which does not advance its brushes until the de-energization of the magnet. The circuit remains in this condition until the subscriber dials the first digit. The in-control switch PI and digit switch D1 operate except as regards the dialling circuit as described in my co-pending application referred to. The digit switches are, however, provided with an extra bank, as shown at C, whilst the in-control switch PI has an additional bank shown at A1.

When the subscriber starts to dial the first digit the line circuit is momentarily opened, as described in connection with Fig. 2. This releases relays HR1 and HR2. Relay HR1 places alternating current on the *a* wire and connects the two polarized relays PR (+) and PR (-) in multiple to the *b* wire. Relay HR1 closes the circuit of relay DTR which operates and locks up over a front contact of relay R1R. The dialling tone is thus removed from the calling line during the remainder of the connection. Relay R1R is a slow release relay which controls the release of the register and performs other functions as described in my co-pending application referred to. It does not fall off during the short time the line circuit is open when the dial is pulled to the finger stop. After the momentary opening of the line the circuit is again closed at this time through the rectifier, as described in connection with Fig. 2. The first pulse is always a positive pulse and thus relay PR (+) operates. In so doing it de-energizes magnet D1 which advances the first digit switch from position 0 to position 1. In position 1 the magnet D1 is again energized, this time over the back contact of relay PR (-) and brush A1 of switch PI. The opening of the back contact of relay PR (+) unbalances the differential relay DR which operates and energizes relay R3R. Relay R3R closes an energizing circuit for the magnet of the in-control switch PI but the brushes of this switch are not advanced. Relay R3R retains energized relay R1R and over another front contact energizes

relay R4R over a circuit from ground, front contacts of R1R, back contacts of relay HR2, front contacts of relay R3R, and winding of relay R4R to battery. Relay R4R locks up over its front contact and a back contact of relay HR2.

On the first reversal of current in the line, relay PR (-) operates and advances switch D1 from position 1 to position 2. Relay PR (+) makes its back contact and again energizes the magnet of switch D1. This continues until the proper number of impulses have been sent in. During the reversal of current which operates relay PR (+) and PR (-) alternately, relay DR1 does not break its front contact, at least long enough to release relay R3R, since the reversals take place almost instantaneously.

At the end of the series of impulses the line circuit is again opened as described with reference to Fig. 2 whereupon both relays PR (+) and PR (-) remain on their back contacts and cause the release of the differential relay DR which releases relay R3R. Relay R3R opens the circuit of the magnet of switch PI which advances from position 1 to position 2. Relay R3R also over a back contact energizes relay HR1 over a circuit from ground, front contacts of relay R1R, back contacts of relay HR2, back contacts of relay R3R, front contacts of R4R and one winding of relay HR1 to battery. Relay HR1 operates and disconnects the alternating current from the *a* wire and in place thereof connects its second winding from ground to the *a* wire and over another change-over contact disconnects the relays PR (+) and PR (-) and in place thereof connects relay HR2 from battery to the *b* wire. When the dial comes to rest and closes the line circuit with the rectifier short circuited, relay HR2 operates in series with the calling line and the second winding of relay HR1. Relay HR2 opens the locking circuit of relay R4R and the circuit of the first winding of relay HR1. Relays HR1 and HR2 remain energized in series until the dial is again pulled for the next selection, after which the second digit switch is advanced in the same manner as the digit switch D1. It will be seen that during the 25 to 50 milli-seconds the line circuit is opened at the end of each selection, the following operations take place in the order given: Relay DR releases, relay R3R releases, relay HR1 operates. All this can easily take place in the minimum permissible time of 25 milli-seconds. The line circuit need remain closed 15 milli-seconds to cause relay HR2 to break its back contact and release relay R4R.

Although the invention has been described as applied to a multi-potential selector system of the kind described in my copending application Serial No. 521,160, filed February 5, 1944, it will be appreciated that it is equally applicable to any type of selector system in which the operation of switching apparatus is controlled by trains of electrical pulses.

Moreover while the detailed description specifically describes subscriber dialling circuits, the invention is of course equally applicable to impulsive over inter-office trunks. In such an arrangement as applied to a system as disclosed in my co-pending application referred to, the impulsive mechanism corresponding to the dial would be located in the A-register and the impulse responding mechanism would be located in the T-register. The scope of the invention is, therefore, only to be construed as defined in the appended claims and numerous modifications

within the spirit of the invention will be readily apparent to those skilled in the art.

What is claimed is:

1. In an electrical signaling system, a signaling circuit, a uni-directional current conducting element, means for connecting said element in said signaling circuit, a source of alternating current, means for coupling said source of alternating current to said signaling circuit, means responsive to direction of current flow, means for connecting said last mentioned means to said circuit, means for intermittently reversing the connection of polarity of said uni-directional current conducting element in said circuit and selective means controllable by said means responsive to direction of current flow.

2. In an electrical signaling system, a signaling circuit, a uni-directional current conducting element, means for connecting said element in said signaling circuit, a source of alternating current, means for coupling said source of alternating current to said signaling circuit, polarized relay means, means for connecting said polarized relay means to said circuit, means for intermittently reversing the connection of polarity of said uni-directional current conducting element in said circuit and selective means controllable by said polarized relay means.

3. In an electrical signaling system, a signaling circuit extending between first and second points, a uni-directional current conducting element, means for connecting said element in said signaling circuit at said first point, a source of alternating current, means for coupling said source of alternating current to said signaling circuit, direction of current responsive means connected to said circuit at said second point, means for intermittently reversing the connection of polarity of said uni-directional current conducting element in said circuit and selective means controllable by said direction of current responsive means.

4. In an electrical signaling system, a signaling circuit extending between first and second points, a uni-directional current conducting element, means for connecting said element in said signaling circuit at said first point, a source of alternating current, means for coupling said source of alternating current to said signaling circuit, polarized relay means, means for connecting said polarized relay means to said circuit at said second point, means for intermittently reversing the connection of polarity of said uni-directional current conducting element in said circuit and selective means controllable by said polarized relay means.

5. In an electrical signaling system, a signaling circuit extending between first and second points, a uni-directional current conducting element, means for connecting said element in said signaling circuit at said first point, a source of alternating current, means for coupling said source of alternating current to said signaling circuit, a pair of oppositely polarized relays, means for connecting said pair of relays to said circuit at said second point, means for intermittently reversing the connection of polarity of said uni-directional current conducting element in said circuit, and selective means controllable by said pair of polarized relays.

6. In an electrical signaling system, a signaling circuit extending between first and second points, a uni-directional current conducting element, means for connecting said element in said signaling circuit at said first point, a source of alter-

nating current, means for coupling said source of alternating current to said signaling circuit, a pair of oppositely polarized relays, means for connecting said pair of relays to said circuit at said second point, back contacts for each of said relays, means for intermittently reversing the connection of polarity of said uni-directional current conducting element in said circuit, selective means, and circuits for controlling said selective means including said back contacts.

5 7. In a telecommunication system, an impulsive circuit extending between first and second points, a uni-directional current conducting element, means for connecting said element in said impulsive circuit at said first point, a source of alternating current, means for coupling said source of alternating current to said impulsive circuit, polarized relay means, means for connecting said polarized relay means to said impulsive circuit at said second point, means for periodically reversing the connection of polarity of said uni-directional current conducting element in said impulsive circuit, selective means at said second point and means for actuating said selective means under the control of said polarized relay means.

15 8. In a telecommunication system, an impulsive circuit extending between first and second points, a uni-directional current conducting element, means for connecting said element in said impulsive circuit at said first point, a source of alternating current, means for coupling said source of alternating current to said impulsive circuit, a pair of oppositely polarized relays, 30 means for connecting said pair of relays to said circuit at said second point, back contacts for each of said relays, means for periodically reversing the connection of polarity of said uni-directional current conducting element in said impulsive circuit, selective means at said second point and circuits for controlling said selective means including said back contacts.

35 9. An impulsive circuit according to claim 8, wherein said selective means comprises a chain of counting relays, a set of code relays, circuits for said code relays controlled by said counting relays and circuits for successively energizing said counting relays responsive to the alternate opening of said back contacts of said polarized relays.

40 10. In a telephone system, a sub-station circuit, a register controller, means for completing an impulsive circuit between said sub-station circuit and said register controller, a signaling device including a uni-directional current conducting element in said sub-station circuit, a source of alternating current, means for coupling said source of alternating current to said impulsive circuit at said register controller, polarized relay means at said register controller, means for connecting said polarized relay means to said impulsive circuit, means included in said signaling device for reversing the connection of polarity of said uni-directional current conducting element in said impulsive circuit a variable and pre-determined number of times, digit storing means in said register controller and means for actuating said digit storing means under the control of said polarized relay means.

45 11. In a telephone system, a sub-station circuit, a register controller, means for completing an impulsive circuit between said sub-station circuit and said register controller, a signaling device including a uni-directional current conducting element in said sub-station circuit, a source of alter-

70 75

alternating current, means for coupling said source of alternating current to said impulsive circuit at said register controller, a pair of oppositely polarized relays, means for connecting said pair of oppositely polarized relays to said impulsive circuit at said register controller, back contacts for each of said relays, means included in said signaling device for reversing the connection of polarity of said uni-directional current conducting element in said impulsive circuit a variable and predetermined number of times, digit storing means in said register controller and means for actuating said digit storing means over circuits including said back contacts.

12. In a telecommunication system, an impulsive circuit extending between first and second points, a uni-directional current conducting element, means for connecting said element in said impulsive circuit at said first point, a source of alternating current, a signaling device at said first point, means responsive to initial operation of said signaling device for connecting said source of alternating current to said impulsive circuit at said second point, means responsive to further operation of said signaling device for reversing the connection of polarity of said uni-directional current conducting element in said impulsive circuit a variable and predetermined number of times, means responsive to direction of current flow, means for connecting said last mentioned means to said impulsive circuit at said second point, selective means at said second point and means for actuating said selective means under the control of said means responsive to direction of current flow.

13. In a telecommunication system, an impulsive circuit extending between first and second points, a uni-directional current conducting element, means for connecting said element in said impulsive circuit at said first point, a source of alternating current, a signaling device at said first point, means responsive to initial operation of said signaling device for connecting said source of alternating current to said impulsive circuit at said second point, means responsive to further operation of said signaling device for reversing the connection of polarity of said uni-directional current conducting element in said impulsive circuit a variable and predetermined number of times, a pair of oppositely polarized relays, means for connecting said pair of relays to said impulsive circuit at said second point, back contacts for each of said relays, selective means at said second point and circuits for controlling said selective means including said back contacts.

14. In a telephone system, a sub-station circuit, a register controller, means for completing an impulsive circuit between said sub-station circuit and said register controller, a signaling device including a uni-directional current conducting element in said sub-station circuit, a source of alternating current, means responsive to an initial operation of said signaling device for connecting said source of alternating current to said impulsive circuit at said register controller, means responsive to a further operation of said signaling device for reversing the connection of polarity of said uni-directional current conducting element in said impulsive circuit a variable and predetermined number of times, a pair of oppositely polarized relays, means for connecting said pair of polarized relays to said impulsive circuit at said register controller, back contacts for each of said relays, digit storing means in said register controller and means for actuating said digit stor-

ing means over circuits including said back contacts.

15. In a telecommunication system, an impulsive circuit comprising two conductors extending between first and second points, a uni-directional current conducting element, means for connecting said element in said impulsive circuit at said first point, a source of alternating current at said second point, a line relay and polarized relay means at said second point, means for connecting said line relay to said impulsive circuit at said second point, a signaling device at said first point, means responsive to initial operation of said signaling device to open momentarily said impulsive circuit to cause said line relay to connect said source of alternating current to one of said conductors and to connect said polarized relay means to the other of said conductors at said second point, means responsive to further operation of said signaling device for reversing the connection of polarity of said uni-directional current conducting element in said impulsive circuit a variable and predetermined number of times, selective means at said second point and means for actuating said selective means under the control of said polarized relay means.

16. In an electrical signaling system, a signaling circuit, a uni-directional current conducting element, means for connecting said element in said signaling circuit, a source of alternating current, means for coupling said source of alternating current to said signaling circuit, a pair of relays, means for connecting each of said relays to said signaling circuit over oppositely poled rectifier elements, means for intermittently reversing the connection of polarity of said uni-directional current conducting element in said circuit and selective means controllable by said relays.

17. In an electrical signaling system, a signaling circuit extending between first and second points, a uni-directional current conducting element, means for connecting said element in said signaling circuit at said first point, a source of alternating current, means for coupling said source of alternating current to said signaling circuit, a pair of relays, means for connecting each of said relays to said signaling circuit at said second point over oppositely poled rectifier elements, means for intermittently reversing the connection of polarity of said uni-directional current conducting element in said circuit and selective means controllable by said relays.

18. In a telephone system, a sub-station circuit, a register controller, means for completing an impulsive circuit between said sub-station circuit and said register controller, a signaling device including a uni-directional current conducting element in said sub-station circuit, a source of alternating current, means for coupling said source of alternating current of said impulsive circuit at said register controller responsive to the completion of said impulsive circuit, relay means at said register controller responsive to direction of current flow, means for connecting said relay means to said impulsive circuit, means included in said signaling device for reversing the connection of polarity of said uni-directional current conducting element in said impulsive circuit a variable and predetermined number of times, digit storing means in said register controller and means for actuating said digit storing means under the control of said relay means.

19. In a telecommunication system, an impulsive circuit extending between first and second points, a uni-directional current conducting ele-

ment, means for connecting said element in said impulsive circuit at said first point, a source of alternating current, means for coupling said source of alternating current to said impulsive circuit, a pair of pulsing relays responsive to opposite directions of current flow, means for connecting said relays to said impulsive circuit at said second point, first and second selective means at said second point, means for periodically reversing the direction of polarity of said uni-directional current conducting element in said impulsive circuit a predetermined and variable number of times, means for actuating said first selective means under the control of said pair of relays, a differential relay having a pair of windings, means for alternately energizing the said windings under the control of said pair of pulsing relays during the transmission of impulses to hold said differential relay operated, and means actuated by the relapse of said differential relay on the termination of the transmission of impulses for transferring the control exercised by said pair of pulsing relays from said first selective means to said second selective means.

20. In a telecommunication system, an impulsive circuit extending between first and second points, a uni-directional current conducting element, means for connecting said element in said impulsive circuit at said first point, a source of alternating current, means for coupling said source of alternating current to said impulsive circuit, a pair of oppositely polarized relays, means for connecting said relays to said impulsive circuit at said second point, back contacts for said relays, first and second selective means at said second point, means for periodically reversing the connection of polarity of said uni-directional current conducting element in said impulsive circuit a predetermined and variable number of times, circuits including said back contacts for controlling the actuation of said first and second selective means, a differential relay having a pair of windings, means under the control of said back contacts for alternately energizing the windings of said differential relay during the transmission of impulses to hold said differential relay operated, and means actuated by the relapse of said differential relay on the termination of the transmission of impulses for transferring the control exercised by said pair of polarized relays from said first selective means to said second selective means.

21. In a telecommunication system, an impulsive circuit extending between first and second points, an impulsive device, means for connecting said impulsive device to said impulsive circuit at said first point, impulse responding relay means at said second point, means for connecting said impulse responding relay means to said impulsive circuit, first and second selective means at said second point, means for actuating said impulsive device to send a predetermined and variable number of impulses over said impulsive circuit, means for actuating said first and second selective means under the control of said impulse responding relay means, a differential relay having a pair of windings, means for alternately energizing said windings under the control of said impulse responding relay means during the transmission of impulses to hold said differential relay operated, and means actuated by the relapse of said differential relay on the termination of the transmission of impulses for transferring the control exercised by said impulse responding re-

lay means from said first selective means to said second selective means.

22. A signaling system according to claim 12 further comprising means for normally short-circuiting said uni-directional current conducting element, means for removing said short-circuit when said signaling device is initially operated and means for momentarily opening said impulsive circuit during the further operation of said signaling device.

23. In a telecommunication system an impulsive circuit extending between first and second points, a uni-directional current conducting element, means for connecting said element in said impulsive circuit at said first point, a source of alternating current, means for coupling said source of alternating current to said impulsive circuit, a pair of relays responsive to opposite directions of current flow, means for connecting said relays to said impulsive circuit at said second point, means for periodically reversing the connection of polarity of said uni-directional current conducting element in said impulsive circuit, a selector switch at said second point and means for actuating said selector switch under the control of said pair of relays.

24. In a telecommunication system, an impulsive circuit extending between first and second points, a uni-directional current conducting element, means for connecting said element in said impulsive circuit at said first point, a source of alternating current, means for connecting said source of alternating current to said impulsive circuit, a pair of relays responsive to opposite directions of current flow, means for connecting said relays to said impulsive circuit at said second point, means for periodically reversing the connection of polarity of said uni-directional current conducting element in said impulsive circuit, a selector switch at said second point, a control magnet for said selector switch, and a circuit for said control magnet directly controlled by contacts actuated by said pair of relays.

25. In a telecommunication system, an impulsive circuit extending between first and second points, a uni-directional current conducting element, means for connecting said element in said impulsive circuit at said first point, a source of alternating current, means for connecting said source of alternating current to said impulsive circuit, a pair of relays responsive to opposite directions of current flow, back contacts for each of said relays, means for connecting said relays to said impulsive circuit at said second point, means for periodically reversing the connection of polarity of said uni-directional current conducting element in said impulsive circuit, a selector switch at said second point, a control magnet for said selector switch and circuits for said control magnet extending over said back contacts of said relays.

26. In a telecommunication system an impulsive circuit extending between first and second points, a uni-directional current conducting element, means for connecting said element in said impulsive circuit at said first point, a source of alternating current, means for connecting said source of alternating current to said impulsive circuit, a pair of oppositely polarized relays, means for connecting said relays to said impulsive circuit at said second point, means for reversing the connection of polarity of said uni-directional current conducting element in said impulsive circuit a predetermined and variable number of times, first and second selector switches at said second

point, control switch for transferring a control exercised by said polarized relays from said first switch to said second switch, a differential relay having a pair of windings, means for alternately energizing the said windings under the control of said pair of polarized relays during the transmission of impulses, and means actuated by the relapse of said differential relay on the termination of the transmission of impulses to operate said control switch.

27. In a telephone system a line circuit, a register controller, means for completing an impulsive circuit between said line circuit and said register controller, a signaling device including a rectifier in said line circuit, a source of alternating current, means for coupling said source of alternating current to said line circuit at said register controller, a pair of oppositely polarized relays at said register controller, means for connecting said polarized relays to said line circuit, means in said signaling device for reversing the connection of polarity of said rectifier in said line circuit a variable and predetermined number of times, first and second digit storing switches in said register controller, an in-control switch for transferring the control by said polarized relays from said first switch to said second switch, a differential relay having a pair of windings, means for alternately energizing the said windings under the control of said polarized relays during the

transmission of a train of impulses, means for momentarily opening said line circuit at the end of said train of impulses, and means actuated by the resultant relapse of said differential relay to advance said in-control switch to transfer the control from said first digit switch to said second digit switch.

28. In a telecommunication system, an impulsive circuit extending between first and second points, a rectifier, means for connecting said rectifier in said impulsive circuit at said first point, a source of alternating current, means for connecting said source of alternating current to said impulsive circuit at said second point, a pair of relays responsive to opposite directions of current flow, means for connecting said relays to said impulsive circuit at said second point, first and second selective means at said second point, means for intermittently reversing the connection of polarity of said rectifier in said impulsive circuit a predetermined and variable number of times, circuits including contacts of said pair of relays for actuating said first and second selective means, means for momentarily opening said line circuit on the termination of a series of rectifier reversals, and means responsive to said opening for transferring the control by said polarized relays from said first selective means to said second selective means.

GERALD DEAKIN.
